UNITED STATES PATENT OFFICE.

JOHN BUCKLEY SEEL, OF LONDON, COUNTY OF MIDDLESEX, ENGLAND.

UMBRELLA.

SPECIFICATION forming part of Letters Patent No. 391,650, dated October 23, 1888.

Application filed August 23, 1887. Serial No. 247,671. (No model.) Patented in England October 21, 1886, No. 13,433.

To all whom it may concern:

Be it known that I, JOHN BUCKLEY SEEL, a subject of the Queen of Great Britain, and a resident of the city of London, in the county 5 of Middlesex, England, commission agent, have invented certain Improvements in Umbrellas, Parasols, and Sunshades, (for which I have obtained Letters Patent in Great Britain, No. 13,433, dated October 21, 1886,) of which the 10 following is a specification.

The object of my invention is to dispense with the springs on the sticks of umbrellas, parasols, and sunshades, usually employed for the purpose of keeping the umbrella, parasol, 15 or sunshade open or shut, and to make the tips lie closely around the stick without the aid of a tip-cup or elastic band. In order to accomplish this purpose, I use ribs and stretchers of any ordinary pattern, except that the 20 ends of the stretchers usually attached to the runner are made of a somewhat different shape and are differently pierced. The ends of the stretchers usually attached to the runner are made to terminate in a fork. Between the 25 30 35 prongs of this fork one end of a flat metal spring, shaped somewhat like a knife-spring, is jointed by means of a rivet, the holes for which are pierced in the prongs of the fork as near to the upper surface—that is to say, the surface nearest to the ribs—as is consistent with strength, and at such a distance from the end as to leave a heel or projecting piece of the fork of about an eighth of an inch in length for a full-sized umbrella. The heel will not need to be so long in smaller umbrellas, parasols, and sunshades, nor do I confine myself to any exact length, that which I describe being the length which I have found most advantageous. The other end of the flat spring is 40 attached to the runner, and when the umbrella, parasol, or sunshade is closed the springs lie nearly flat in longitudinal grooves in the runner just deep enough and wide enough to contain them, and a metal ring forming part of 45 the runner surrounds and holds them down at about one-third, or, as I find it better, nearly one-half, of their length from the point of their attachment to the runner. The remaining portion of their length remains free 50 to be bent and raised away from the runner by any force tending to thrust away from the run-

ner the ends of the springs jointed to the stretchers; but the elasticity of the springs constantly tends to oppose such force. I find it better that the ring surrounding the springs 55 should be slotted to receive the springs and hold them in their places. A plain ring has, I am aware, been previously used for a somewhat similar purpose, and I do not claim as my invention a plain ring so used. As long 60 as the stretchers lie along the stick in the position which they occupy when the umbrella, parasol, or sunshade is closed the springs are in a condition of rest; or if, as I find preferable, the heel of the stretcher-fork has a slight nose 65 or projection toward the runner, the stretchers, and with them the ribs, will be pressed against the stick. If now the runner be pressed upward, the stretchers at once begin to act as levers, of which the heels pressing against the runner are the shorter arms, and raise the springs, thus bringing their elasticity into play, and that elasticity opposes the opening of the umbrella, parasol, or sunshade up to the point 70 at which a line joining the point of the heel of each stretcher with the rivet attaching such stretcher to its spring makes an angle of nearly ninety degrees with the longitudinal axis of the runner. This point may be called the "dead-point." As the runner is pushed beyond that 75 point the elasticity of the spring operates in favor of the opening. I can increase the action of the springs at the most desirable points by giving a special form to the heels of the stretchers, so that a comparatively small point 80 bears upon the runner at the dead-point, and rounding off the lower edges, which come to bear on the runner when that point is passed, so that the action of the springs is almost continuous either in the one direction or the other. 85 Instead of the ends of the stretchers being forked and the ends of the springs inserted in the forks, the ends of the stretchers may be single and the ends of the springs may be forked; and instead of the springs being quite 90 flat they may have a longitudinal curvature, with the concavity toward the runner, which will cause them to exert a pressure upon the stretcher ends, pressing them toward the runner even without the nose upon the heel of the 95 stretcher, to which I have previously referred, and in the position in which I have before de- 100

scribed them as being in a condition of rest. The amount of this curvature may vary with the length and stoutness of the spring. The shorter and stouter the spring the less the curvature that will be required to produce a similar effect. The ends of the stretchers, instead of operating directly against the runner, may operate against a groove or channel in a metal collar, preferably of hardened steel, which slides freely upon the runner, thus obviating the wearing of the runner by the friction of the ends of the stretchers and greatly facilitating the action. The lower ends of the springs may be covered by a thin metal sleeve, which may either be in one piece with or separate from a boss or flange which is screwed upon the handle end of the runner for the fingers to press against; but I do not claim the sleeve or the boss or flange in itself as my invention, each of such contrivances having been, as I am aware, previously used.

The action is as follows: The umbrella being closed, the pressure of the springs on the stretchers causes the ribs to lie close to the stick. Upon the runner being pushed upward from the handle of the umbrella, the stretchers at their junctions with the ribs rise up from the stick and raise the springs, which tend to press them against the stick. When the umbrella is about half open, the peculiar shape of the heels of the stretchers causes the springs to act in the reverse way, the effect now being to assist the opening of the umbrella. The stretchers I prefer to make a little longer than usual, so that when the umbrella is open they will pass the horizontal position upward toward the notch, and when the umbrella is closed they will allow the end of the runner to project beyond the tips. The runner may be stopped from rising beyond the proper position, when the umbrella is fully open, by a pin in the stick.

In the accompanying drawings, Figure 1 is an elevation of the runner which I use. A A are the grooves in which the springs rest. These grooves may either be continued up to the ring B, under which the springs slide, as shown in Fig. 1, or they may extend for only a short length—say about the third of an inch—along the runner, so as to make a sort of notch for attaching the springs, as shown in Fig. 2, the springs being partly held in their places by passing through slots in the ring B, which are shown in Fig. 9, or by the ring itself, when the ring is made without slots. At the lower end of the lugs or projections which lie between the grooves small notches R R are cut equidistant from the lower end of the runner, for the purpose of securing the wire which fastens the springs into their places.

Figs. 3 and 4 show the steel collar which slides freely on the runner, with a groove or channel, D, for the stretcher ends to bear against.

Figs. 5 and 6 show a stretcher having a forked end with the steel spring Q attached to it by a rivet at E.

Figs. 7 and 8 show a stretcher with a single end, a spring having a forked end, and being attached to it by a rivet at E.

Fig. 9 shows the ring B with slots for keeping the springs in their places. I prefer to make this ring in one piece with the runner.

Figs. 10 and 11 show a knob or push-piece to be screwed on to the end of the runner nearest the handle of the umbrella and carrying a sleeve which will cover the greater part of the springs.

Figs. 12 and 13 show the spring as attached to a forked stretcher, and with the groove F, for the purpose of receiving a wire to fasten it in its place.

Figs. 14 and 15 show the spring when fastened to a stretcher with a single end.

Fig. 16 is an elevation of the runner with the springs fixed in their places. This is done by passing the spring under the ring B and sliding it into the groove A, and then twisting a wire around the notches R R in the springs and runner. There is a great advantage in the simplicity of this operation.

Fig. 17 shows a section on the line L M in Fig. 16.

Fig. 18 shows a section through the runner with the stretcher P and spring Q in position when the umbrella is open. The collar C, the ring B, and the push-piece T, with the sleeve S, are also shown.

Fig. 19 shows an elevation of the runner complete with the stretcher in the position when the umbrella is closed.

Fig. 20 shows the complete umbrella-frame open.

Having now particularly described and ascertained the nature of my said invention and in what manner the same is to be performed, I declare that what I claim is—

1. In an umbrella, parasol, or sunshade, the combination, with a runner provided with longitudinal grooves, of a series of springs lying in said grooves and connected at their upper ends to stretchers, substantially as described.

2. In an umbrella, parasol, or sunshade, the combination, with the grooved runner, the flat springs, and the slotted ring placed around the said runner, of a wire passing around and resting in notches in the lower ends of the runner and springs, substantially as described.

3. In an umbrella, parasol, or sunshade, a runner grooved for the reception of springs, and the sliding collar having a groove around its outer surface, substantially as described.

4. In an umbrella, parasol, or sunshade, the runner fitted with a ring provided with slots for the reception of the flat springs, and also with a collar provided with a groove around its outer surface, and adapted to slide up and down on the runner in engagement with the inner ends of the stretchers, substantially as described.

5. In an umbrella, parasol, or sunshade, a runner fitted with a sliding collar grooved around its outer surface, and with a stretcher,

the inner ends of which engage the groove in the sliding collar, substantially as described.

6. In an umbrella, parasol, or sunshade, the combination of a runner fitted with a collar 5 having a groove around its outer surface, a slotted ring, and the pushing-piece having the sleeve S, substantially as described.

7. In an umbrella, parasol, or sunshade, a grooved runner having springs attached 10 thereto by being passed under the slotted ring B, and held in the grooves of the runner by a wire passed around and resting in notches in the grooves and springs, substantially as described.

15 8. In an umbrella, parasol, or sunshade, the combination of a runner having longitudinal

grooves, a sliding collar having a groove around its outer surface, a slotted ring, a knob or push-piece with protecting-sleeve, and springs resting in the grooves of the runner at 20 their lower ends, and attached at their upper ends to the inner ends of the stretcher, and adapted to press said inner ends of the stretcher inward, substantially as described.

Dated the 4th day of August, 1887.
